UNITED STATES PATENT OFFICE.

MUNSON H. TREADWELL, OF NEW YORK, N. Y., AND CARL P. ASTROM, OF ORANGE, NEW JERSEY, ASSIGNORS TO M. H. TREADWELL COMPANY, A CORPORATION OF NEW YORK.

DUMPING-CAR.

No. 892,885.

Specification of Letters Patent.

Patented June 30, 1906.

Application filed January 15, 1902. Serial No. 410,375.

To all whom it may concern:

Be it known that we, MUNSON H. TREADWELL and CARL P. ASTROM, citizens of the United States, residing at New York, in the county of New York and State of New York, and Orange, county of Essex, and State of New Jersey, respectively, have invented certain new and useful Improvements in Dumping-Cars, of which the following is a full, 10 clear, and exact specification.

This invention relates to end dumping cars, and has particular reference to the construction of a car frame and the mounting of a car body thereon, whereby the car frame 15 may be coupled in a train at either end, and also to a frame construction whereby the car body may be dumped at either end without interference with the coupling devices and without requiring the car frame to be of excessive length.

A further object of the invention is to provide motor means for actuating the car body, and a particular feature thereof resides in the provision of means whereby the car body 25 may be moved by an operating cylinder through a distance greater than the effective stroke of the cylinder by varying the length of the piston rod between the piston and the point of application of the power to the car 30 body.

In carrying out these objects, and other objects which will more fully appear herein-after, the car frame is provided with upright sides on which the car body is mounted 35 to be tilted or moved longitudinally, connected by an underframing extending beneath the car body and disposed so as not to interfere with the longitudinal movement of the car body to and from dumping position.

40 By such construction, a very short frame is provided, so that a single truck car can be made which will be capable of easily going around sharp curves and without any tendency of being thrown from the track, as 45 would be the case with a long frame mounted on a single truck. As herein shown a fluid pressure operated motor is provided to actuate the car body, preferably comprising a stationary cylinder having its piston rod 50 connected to the car body, which latter is supported on the side frames by trunnions in such manner that it is simultaneously tilted and moved longitudinally of the car frame in dumping. To actuate the car body 55 in either direction from its normal upright

position with relatively short cylinder, a piston rod is provided which can be telescoped or shortened for operating the car body from its normal upright position towards one end of the car frame, and which can be lengthened when it is desired to operate the car body from the central upright position towards the opposite end of the car frame. In order to permit the car body to be coupled to a train from either end, and at the same time prevent the coupling devices from interfering with the dumping of the car body at the coupling end, or necessitating a long frame, the coupling devices are mounted on the car frame in such manner as to be capable of being swung out of the way when the car body is to be dumped at that end.

The invention with reference to the preferred forms thereof is shown in the accompanying drawings, wherein

Figure 1 is a side elevation of a dumping car embodying the invention, and showing an actuating cylinder having a stroke equal to the total movement of the car body. Fig. 2 is a detail view showing an actuating cylinder and a telescoping piston rod, whereby the stroke is only half the total movement of the car body. Fig. 3 is an end elevation of the car embodying the invention, and Fig. 4 is a detail view showing the cross head and cross head guide.

1, 1 represent upright side frames having slots in which axle boxes 2, 2 are mounted.

3 are wheels carried on axles 4 in the boxes 2, between which and the car frame springs 5 90 may be provided in the usual manner.

The upright side frames 1 are connected by transverse underframes 6, preferably of I-beam cross section and bolted to the side frames between the wheels and in an inclined direction as shown in Figs. 1 and 3 in order to provide a rigid connection. The underframes 6 are curved downwardly in the middle in order to permit the lower end of the car body 7 to pass over them in either 100 direction as it is dumped. Pivoted at each end of the side frames and extending across the car frame are draft bars 8 secured to the side frames by pins 9, and carried by the draft bars 8 are the usual train couplings 10 105 with interposed spring draft rigging 11. By removing one of the pins 9, the draft bar can be swung outwardly on the other pin as a hinge, thereby removing all obstruction to the dumping of the car body at that end, and 110

when the car is to be coupled in a train the draft bar can be swung back and the pin replaced. By this means considerable switching and turning of the car will be avoided, 5 since with this coupling and draft gear it is unnecessary to have the car at the end of the train, except when it is to be dumped.

Heretofore, cars dumping at one end only have been used, and such cars have not been 10 equipped with couplings at the dumping end so that it has been necessary to switch or turn these cars around considerably in order to get the dumping end at the right position. With this construction herein, it is possible 15 to avoid all this switching and turning inasmuch as the car can be coupled from either end.

The upright side frames 1 each have a shelf 13 on which is mounted a bracket 14 20 having a horizontal track 15 on which trunnions 17 connected with the car body 7, as by a yoke 18, roll. The brackets 14 also have racks 19 on which roll gears 20 keyed to the trunnions 17, so that as the body is moved 25 longitudinally of the car frame, it simultaneously tilts. In order to actuate the car body, a power cylinder 23 is provided, having a piston 24 and a piston rod 25 connected by a strap 26 with one of the trunnions 17. 30 As shown in Fig. 1, the car body is at its upright central position and the piston 24 midway of the cylinder 23, and a four-way valve 31 admits pressure through one or the other of pipes 27 or 28 to one side of the piston and 35 opens the other side to the exhaust. To move the car body the fluid pressure may be admitted by means of an inlet 32 and is exhausted through a pipe 33 in a well known manner. The piston rod 25 carries a cross-head 29 which straddles one of the racks 19 and slides on a guideway 30 (Fig. 4). As 40 shown in Fig. 1, it will be observed that cylinder 23, having a length equal to the total movement of the car body, may be so long as 45 to interfere with the dumping of the car body at that end, or require lengthening of the frame in order to attach the draft bar 8.

In order to permit of shortening the car frame, and also decrease the weight, the 50 mechanism shown in Fig. 2 may be used. In this figure, the parts other than those shown will be exactly like Fig. 1 save that the side frames 1 at the cylinder end may be somewhat shorter. In Fig. 2, the piston rod 25 55 is made hollow and has a cross head 28 fixed thereto as in Fig. 1. Between the rod 25 and the strap 26 in Fig. 2 is interposed a supplementary additional section of piston rod 35 having shoulders 36 cut therein at a distance 60 apart equal to the longitudinal distance the car body will move in going from its central position to its extreme outward position in either direction. The end of the rod 25 is threaded and carries a nut 38 thereon. 65 Mounted to embrace the nut and to extend

in the one or the other of the slots 36 is a divided collar 39 held by bolts 40. By releasing the bolts 40 and removing the collar 39, the piston rod 25 and the strap 26 will be disconnected. If now steam or air be admitted on the right side of the piston 24 in Fig. 2, it will be moved towards the left without moving the strap 26 or the rod 25. As soon as the end of the rod 25 goes over the left hand shoulder 36 on the rod 35, the piston 24 will be at or about the extreme left end of the cylinder and the collar 39 can be replaced, thereby again coupling the piston rod 25 and the rod 35, and making the piston rod longer than it was before. If pressure be now admitted behind the piston 25 at the left end of the cylinder, the car body will be moved and dumped towards the right end of the frame and can be brought back to central position by reversing the pressure. In order 80 to dump to the left the piston rod will be shortened. Fig. 2 shows this condition in which the car body will be dumped to the left when pressure is admitted at the right end of the cylinder. The side frames are 85 provided with stops 42 at the left end against which the trunnions 17 will strike, and a similar stop 43 is provided on the left or cylinder end, on the side opposite the cylinder to check the movement in that direction. At 90 the same time that the trunnions 17 strike the stops 42 or 43, the lower side of the car body will rest on the end frame 6 as shown in dotted lines in Fig. 1, so that the car body will be positively stopped at separated points 95 without tending to have the piston strike the end of the cylinder. In practice, suitable latches or mechanical locking devices may be used to hold the car body in upright position during transportation. 100

From the foregoing description, it will be seen that a double end dumping car is provided which may be mounted on a single truck, by reason of its shortness between couplings, and which will not tend to be pulled off the track in going around curves, as happens where the frame has too great an overhang beyond the wheels. Also, it is possible to construct a short frame by reason of the underframe extending under the car 115 body, and also supporting the car body at either end, in dumped position. It will of course be understood that the dimensions of the frame and side of the ladle will be determined according to the requirements of actual practice, and in some instances it may also be necessary to flare the side frames in order to permit the car body to clear. 120

While a motor is herein shown mounted on the frame for operating the car body, it is 125 not to be understood that the invention is limited to motor means for operating the car body inasmuch as manual devices can be mounted on the frame herein described for operating the car body. Such operating de- 130

vices will likewise permit of the use of the short frame construction herein shown and described, and forming a part of this invention.

5. Various modifications and changes in the specific construction herein described may be made without departing from the scope of the invention.

Having thus described our invention, we 10 declare that what we claim as new and desire to secure by Letters Patent, is,—

1. The combination with a car frame comprising sides and an underframe connecting the sides, of a car body supported by the 15 sides and mounted to tilt between the sides and above the underframe, and a motor having connections for tilting the car body.

2. The combination with a car frame comprising sides and an underframe connecting 20 the sides, of a car body supported by the sides and mounted to tilt between the sides and above the underframe, and a reciprocating motor having connections for tilting the car body.

25. 3. The combination with side frames provided with tracks, of a body supported thereby and mounted to tilt and move longitudinally thereon in either direction from a central upright position, a cylinder mounted thereon, and an actuating connection between the cylinder and the body.

4. The combination with side frames provided with tracks, of a body supported thereby and mounted to tilt and move longitudinally thereon in either direction from a central upright position, a cylinder mounted thereon, a trunnion carried by the car body, and a strap engaging the trunnion and connected to the piston rod.

40. 5. The combination with a motor operated end dumping car comprising a car body mounted to move away from the center towards one end to dump, and a power operated motor, of a supporting frame having car body supports at opposite sides, and an underframe beneath the car-body connecting the side frames.

5. The combination with a car-body mounted to move away from the center towards one end to dump, of a frame having sides adapted to support the car body at opposite sides, and an underframe connecting the sides beneath the car body, and between the ends.

55. 7. The combination with a frame comprising upright sides having car body supports, and a longitudinally movable car-body supported thereby at opposite points, of a cross brace connecting the side frames beneath the car body and between the ends, whereby to leave the ends unobstructed.

8. The combination with a frame comprising upright sides having each a track, and a transverse underframe connecting the side 65 frames, of a car body mounted to move longi-

tudinally on said tracks from a central position in either direction and disposed above said underframe.

9. The combination with a frame comprising upright sides having each a track, and a transverse underframe connecting the side frames, of a car body mounted to move longitudinally and simultaneously tilt to a discharging position in opposite directions from a central upright position, said underframe 75 being beneath the car body.

10. The combination with a frame comprising upright sides having each a track, and an understructure connecting the side frames, of a car body mounted to move longitudinally and simultaneously tilt in either direction from a central upright position to rest on said understructure when tilted.

11. The combination with a movable car-body mounted between oppositely disposed side frames to tilt and simultaneously move longitudinally in opposite directions from a central upright position, of an underframe extending beneath the car-body and connecting the side frames, and coupling devices at each end.

12. The combination with a movable car-body mounted between oppositely disposed side frames to tilt and simultaneously move longitudinally in opposite directions from a central upright position, of an underframe extending beneath the car-body and connecting the side frames, and removable coupling devices at each end.

13. The combination with a movable car-body mounted between oppositely disposed side frames to tilt and simultaneously move longitudinally towards the end of the frame to a discharging position, and an underframe extending beneath the car-body and connecting the side frames, of a coupling device at the discharging end mounted to be removable to permit movement of the car-body to the discharging position.

14. The combination with a movable car-body mounted between rigidly connected side frames and supported thereby, of means for simultaneously moving and tilting the body to a discharging position towards one end of the frame from the center, and removable coupling means at the discharging end.

15. The combination with a movable car-body mounted between rigidly connected side frames and supported thereby, of means for simultaneously moving and tilting the body to a discharging position towards one end of the frame, and coupling means at the discharging end carried by the side frames and mounted to be removable to permit 125 dumping the car-body at the coupling end.

16. An end dumping car comprising a frame mounted on wheels, a car-body mounted to move longitudinally between side frames to dump at either end, motor means 130

for actuating the car-body, and an under-frame forming an abutment for the car body when in dumping position.

17. An end dumping car comprising a frame mounted on wheels, a car-body mounted to move longitudinally between side frames to dump at either end, motor means for actuating the car-body, an underframe forming abutments for the car-body when in dumping position, and coupling means carried by the frame and dismountable to permit dumping of the car-body.

18. An end dumping car comprising a car-body mounted to dump at the end, of a frame consisting of sides supporting the car body, and an underframe constructed to support the car-body when in dumping position.

19. An end dumping car comprising a car-body mounted to move longitudinally in either direction from a central position to dump at either end, and a single truck supporting frame comprising sides and an underframe rigidly connecting the sides beneath the car-body and between the wheels.

20. An end dumping car comprising a car-body mounted to move longitudinally in either direction from a central position to dump at either end, and a single truck supporting frame comprising sides and underframes inclined to each other and rigidly connecting the sides beneath the car-body and between the wheels.

21. An end dumping car comprising a car-body mounted to dump at the ends of a frame consisting of sides supporting the car-body, and connected by underframes be-

neath the car body and between the ends of the frame, and removable coupling means at the ends of the frame.

22. An end dumping car comprising side frames, an underframe, and a car-body carried by the side frames and extending below the top of the underframe, and means for tilting and longitudinally moving the car body whereby to clear the underframe.

23. The combination with a supporting frame, of a car-body mounted to move longitudinally in opposite directions from an upright central position, a cylinder and piston rod for actuating the car-body, the stroke of the cylinder being less than the total bodily movement of the car-body, and means for varying the relative position of the cylinder and piston rod independently of the car-body.

24. The combination with a supporting frame, of a car-body mounted to move longitudinally in opposite directions from an upright central position, a cylinder and piston rod for actuating the car body, the stroke of the cylinder being less than the total bodily movement of the car body, and means for varying the effective length of the piston rod independently of the car body, said piston rod being telescopic to vary in length.

In testimony whereof we affix our signatures, in presence of two witnesses.
